COMBINED TRY AND MITER SQUARE

Ronald David Carter, Leamington Spa, England, assignor
to Stanley Works (Great Britain) Limited, Woodside,
Sheffield, England

Filed Oct. 5, 1970, Ser. No. 25,321

Claims priority, application Great Britain Apr. 17, 1970

Term of patent 14 years

Int. Cl. D10—04

U.S. Cl. D52—6

FIG. 1.

FIG. 2.

FIG. 3.

FIG. 4.

FIG. 5.

FIG. 6.

FIG. 1 is a front perspective view of a combined try and miter square showing my new design;

FIG. 2 is a rear elevational view thereof;

FIG. 3 is a right side elevational view thereof;

FIG. 4 is a left side elevational view thereof;

FIG. 5 is a top plan view thereof; and

FIG. 6 is a bottom plan view thereof.

The bracketed ruler portions are broken-away to illustrate indeterminate length.

I claim:

The ornamental design for a combined try and miter square, as shown and described.
